UNITED STATES PATENT OFFICE.

LAWRENCE A. BURCH, OF JAMESTOWN, NEW YORK.

CHUCK.

Application filed December 7, 1922. Serial No. 605,459.

To all whom it may concern:

Be it known that I, LAWRENCE A. BURCH, a citizen of the United States, residing at Jamestown, in the county of Chautauqua and State of New York, have invented certain new and useful Improvements in Chucks, of which the following is a specification.

This invention has to do with improvements in tool appliances and more especially to those tool holding devices known as chucks.

The object which it is aimed to accomplished by these improvements is greater facility in the adjustment of the jaws of the chuck to quickly reach the position of and produce clamping action upon the tool or other object which is inserted into the chuck jaws.

20 In carrying out this end, I have provided for a dual adjustment, the one a general adjustment to bring the jaws into engaging relation to the tool, and another, a relatively fine adjustment, for producing final clamping action.

It is further contemplated as an important feature of my invention to provide such a construction and arrangement of jaw actuating parts that the jaws may be instantaneously adjusted to any size of tang within the capacity of this device through the employment of an interrupted thread construction which permits of sliding movement of one part with respect to the other to carry 35 the jaws to gripping position preliminary to the clamping action obtained by rotation of said parts.

With the above and other objects in view, the invention consists in certain combinations and arrangements of the parts as will more fully appear as the description proceeds, the novel features thereof being pointed out in the appended claims.

In the drawings:

45 Figure 1 is a side elevation of an embodiment of this invention.

Figure 2 is a vertical sectional view.

Figure 3 is a similar view to Figure 2, taken at right angles to the section of said figure.

Figure 4 is an end elevation of the lower extremity of the chuck.

Figure 5 is a horizontal sectional view of the device.

55 Figure 6 is a perspective view of the chuck holder or inner actuating member.

Figure 7 is a perspective view of the outer or sleeve actuating member for the jaws.

Corresponding and like parts are referred to in the following description and indicated in all of the views of the drawings, by like reference characters.

Referring to the drawing, 1 designates a socket or sleeve, the exterior of which is suitably knurled in the customary manner to afford adequate hand hold in the use of this device. The bore at the lower end of the sleeve is conical in form, narrowing toward the entrance, so as to produce a beveled camming surface 1^a with which the jaws 2 coact. These jaws are arranged in substantially parallel spaced relation and have their inner faces suitably serrated or toothed to obtain sufficient gripping action upon a tool received therebetween to insure against slippage. A re-bent spring wire 3 interposed between the jaws tends to hold them apart and against the camming surface above referred to and the ends of the spring are preferably secured in openings in the jaws to preclude displacement of the parts. These jaws are adjusted by two actuating parts, one the hollow core 4, which, for the purpose of this description I term the jaw holder, and the other the nut or sleeve 5. The core, which is best shown in Figure 6, is slotted the major portion of its length so as to receive the jaws which seats in the slots and against the nut 5 at the top, as best seen in Figure 3. The upper end of the core is provided with a socket 6 in which the shank of an operating tool is positioned, as set forth in the companion application for my improvements in combination tools, filed December 7, 1922, Serial No. 605,457. Externally the core is formed with heavy threads 7 which at diametrically opposite points are interrupted, the nut or sleeve 5 being formed with corresponding threads internally thereof, as indicated at 8, also having opposite points of interruption. Externally the nut 5 is formed with fine threads 9 which engage corresponding threads in the upper end of the socket 1.

There are two additional features residing in the provision of a stop pin 10 at the lower end of the core which prevents the longitudinal displacement of the part unless the nut 5 is withdrawn from the sleeve 1, and a stop rib 11 on the interior

of the nut 5 at the end of one of the sets of threads, which limits the rotative movement of the core with respect to the nut and causes these parts to jointly adjust up-
5 on the socket.

While I have shown in this embodiment an interrupted thread construction, I desire it to be understood that this is not essential, but it is preferably employed be-
10 cause of the additional facility of adjustment which is procured thereby. In other words, let us assume the tang of the tool which is to be introduced into the chuck is of relatively small diameter; it is unnec-
15 essary that the actuating nut 5 and the core 4 be screwed inwardly to bring the jaws into engagement with the tool because this may be accomplished by turning the core until these threads are disposed in the in-
20 terrupted thread space of the nut (the rib 11 insuring against overrunning of the rotative movement in this operation) whereupon the core may be slid downwardly or inwardly freely, carrying the jaws downwardly and
25 closing them upon the tang by virtue of their contact with the camming surface 1^a. The clamping action may now be obtained by slight rotation of the core bringing the threads 7 and 8 into action. In just the re-
30 verse manner a very quick displacement or opening of the jaws of the tool is accom-
plished by disengaging the threads and sliding the core outwardly of the shell 1.

In general, however, there are two main
25 adjustments which are obtained by this construction of differentially threaded parts 4 and 5. That is to say, when the tool is inserted between the jaws, the core 4 is first rotated to engage the jaws with the tool,
40 followed by rotation of the nut which with its relatively fine threads secures the final clamping adjustment and securely holds the jaws at the adjusted position. One of the
45 advantageous features of this arrangement lies in the fact that the two rotative ac-
tions of the parts 4 and 5 are really capable of attainment by actuation of one of the parts. For example, when the tool is in-
50 serted into the jaws the part 4 is rotated by a handle member and the action of the coarse threads produces a movement of the jaws until the threads bind owing to the
55 contact of the jaws with the shank of the tool and continued movement of this mem-
ber brings the ends of the threads 7 there-
on into engagement with the rib 11 upon the
nut which will cause the nut 5 to take up
rotative movement and produce the final
clamping action.

60 Such a tool or appliance as above described

may be used in connection with braces, drills and with other implements, or ma-
chines where it is desired to employ a tool holding device, and I contemplate that the
jaw holding member 4 may be suitably
65 modified to adapt it to the particular type
of device with which it is to be used with-
out changing the essential characteristics of
this invention.

Having thus described my invention, what
70 I claim as new and desire to secure by Letters Patent, is:

1. A tool holding device of the class de-
scribed comprising a socket, a pair of jaws
75 mounted therein, a jaw holder for adjust-
ing the jaws by reciprocal movement with
respect to the socket, an independent ad-
justing means for said jaws disposed in-
80 termediate the holder and the socket, means
upon the adjusting means to engage the jaw
holder and effect joint rotation therewith,
and means upon said adjusting means for its
rotative adjustment relative to the socket.

2. A tool holding device of the class de-
scribed comprising a socket, a pair of jaws
85 mounted therein, a slidable part coacting
with the jaws for adjusting the same, a sec-
ond part having threaded connection with
the first part and with the socket, and means
90 on the second part for engaging the slidable
part for joint rotation in the socket where-
by clamping action of the jaws may be ob-
tained by a successive sliding and rotary
movement of the parts.

3. A tool holding device of the class de-
scribed comprising a socket, a pair of jaws
95 mounted therein, a slidable jaw holder for
actuating the jaws to adjust the same, a
nut having an interrupted threaded con-
nection with the jaw holder for sliding
100 movement thereof, and a continuous threaded
connection with the socket for inde-
pendently adjusting the jaws, and means
upon the nut for limiting its rotative move-
ment upon the holder and for engaging said
105 holder for joint rotation.

4. In a tool holder of the class described
comprising a socket, a slotted jaw holder
having interrupted threads upon its surface,
a pair of jaws mounted therein, an adjust-
110 ing nut having a continuous exteriorly
threaded connection with the socket and an
interrupted interior thread to receive the
holder, and a stop member upon the nut to
engage the holder in its rotative movement
115 and effect joint rotation therewith in the
socket.

In testimony whereof I affix my signature.

LAWRENCE A. BURCH.
